RADIO RECEIVER CIRCUIT

Lemuel M. Temple, Scarsdale, N. Y.

Application September 20, 1939, Serial No. 295,712

4 Claims. (Cl. 179—171)

My invention relates to radio receivers and more particularly to receivers operated with a high voltage dry battery commonly known as a "B" battery.

The principal feature of my invention is the provision of means in the output circuit of the receiver to reduce the B battery current used by the output tube and thereby markedly extend the useful life of the B battery with consequent reduction in renewal battery and operation cost.

My invention is based upon observations of the fact that many radio receivers are operated by their owners at a substantially lower power output level, that is, so called volume or listening level, than that for which the receiver is designed or rated; and a realization of how the receiver output may be controlled in accordance with this practice and effect marked economy in the life of the B battery.

The usual battery type receivers are designed to give a power output of about 200 to 500 milliwatts with a common average of around 325 milliwatts. Many users of such receivers however maintain the output or volume at a substantially lower level, i. e. around 50-100 milliwatts. This is especially true of battery receivers used in the country with quiet surroundings which do not require high volume. This normal control by the user of the radio set, however, does not effect any economy in the operation of the B battery since the B current used is unchanged when the usual class A type amplifier is used.

In accordance with my invention I have provided in the receiver circuit means for controlling the output of the receiver to the usual reduced listening level and for reducing the B battery current consumption proportionally. This reduction in B battery current used by the output tube in the receiver is as much as 50% of the normal consumption and may range as high as about 65%. The B battery current consumption is regulated in accordance with my invention by an arrangement for overbiasing the output tube; that is, increasing the normal bias on a grid or grids in the output tube so as to reduce the plate current drawn by that tube. The device embodying my invention also includes means whereby the over-biasing of the output tube may be manually reduced and the biasing of this tube returned to a value for maximum performance. By this arrangement if the voltage of the B battery has dropped materially so that the set no longer is giving satisfactory performance, the reduction of the bias on the control grid of the

output tube has the effect of permitting a greater amount of current to flow from the B battery and satisfactory performance of the set can thereby be restored for an additional period, which will be valuable, even though the drain on the B battery during this period will be very heavy.

The means for effecting this overbiasing may be in the form of an added resistance in the plate control-grid circuit, or taps on the B battery with a variable connector to utilize varying amounts of voltage from this battery applied to the screen grid of the output tube, or a combination of these two means. The added grid biasing resistor is the preferred arrangement from the standpoint of simplicity of construction and operation. A switch is also provided for electrically disconnecting this over-biasing resistor from the grid circuit, when the current supply from the B battery has been reduced, by use of the battery, to a point where further limiting the current would adversely affect the operation of the receiver, that is, reduce the power output to an undesirably low listening level.

The cost of power from dry batteries is very high in comparison with metered power and a saving of battery current consumption is vital to the economically successful use of dry battery receivers. Furthermore, the B current used by the output tube or tubes is large compared with the other tubes in the set, and generally constitutes from about one-third to one-half of the total current consumption. Accordingly I have incorporated my B battery current saving arrangement in the circuit of the output tube.

It is to be noted that the useable life of a B battery is seldom determined solely by the decline of battery voltage to a point where there is insufficient voltage to operate the tubes of a receiver. Normally the life of a B battery is determined by the decline of receiver performance such as sensitivity of the receiver, audio frequency distortion, and loss of power output at the loud speaker. These factors effectively determine the B battery life because they determine the receiver performance and when this becomes unsatisfactory to the listener the B batteries are discarded and replaced by new batteries. Nevertheless, the discarded B batteries have not delivered their full power, but have become unsatisfactory due to the loss of B voltage.

Because of this declining B voltage and because of variations in the operation of the receiver due to different locations of the receiver with respect to the transmitting station, satisfactory

operation is most effectively obtained by the use of a self-biasing output tube circuit. Such a circuit provides automatic adjustment of the bias voltages on the tubes during the decline of the B battery. The B battery current controlling means of my invention is therefore preferably used in a self-biasing output tube circuit. Also the switch means which I employ enables the B battery current reducing means to be eliminated electrically from the circuit when the B battery has declined through use to an unsatisfactorily low level. At this point the switch may be employed to return the output circuit to its normal self-bias condition, and thereby effectively increase the current supplied from the B battery during the remainder of its use in the circuit. In the usual case, my current saving arrangement may be employed for about the first half of the life of the B battery.

The novel features and details of my invention will be further understood by reference to the accompanying drawing, in which:

Figure 1 is a circuit diagram showing the adaptation of my invention in the output circuit of a battery operated radio receiver; and

Figure 2 is a graph showing the difference in B battery current consumption and life with the usual self-bias battery receiver and the same type of receiver utilizing the current reducing means of my invention.

Referring now to Figure 1 the circuit shown therein is an output circuit of a conventional type receiver having one pentode tube as the output tube. It is to be understood, however, that two or more output tubes may be used if desired; a common example being two output tubes connected in push-pull arrangement. For the sake of simplicity, only the last output stage has been illustrated in this figure, and legends given on the drawing to indicate the conventional connections of this output circuit with the preceding portion of the radio circuit, e. g. detector or amplifier circuit.

The output circuit shown in Figure 1 comprises, generally, a pentode output tube 10, an output transformer 11, and loud speaker 12, a B battery 13, two biasing resistors 14 and 15, and a switch 16. A resistor 17 and condenser 18 are provided for connecting the output tube to the detector or audio driver. The other connectors are indicated on the drawing. The B battery 13 supplies positive voltage to the plate 19, and screen grid 20 and negative voltage to the control grid 21. The voltage applied to the filament 22 is supplied from the A battery, not shown, but indicated. The normal grid biasing voltage applied to the control grid 21 in the self-biasing arrangement shown in this figure, is controlled by the grid resistor 14, and in the conventional operation of this circuit only this resistor is used to regulate the grid bias.

Now to operate the above described circuit in accordance with my invention and thereby conserve the B battery current, an additional grid resistor 15, shown in Figure 1 is electrically connected in the grid biasing circuit by opening the switch 16; it is to be noted that when this switch is closed that the resistor 15 will be shunted and the current will follow the path of least resistance around this resistor and through the switch 16. However, when the switch 16 is open current flows directly through this circuit including additional resistor 15.

The effect of electrically adding the additional resistor 15 in this circuit is to reduce the amount

of plate current drawn by the output tube 10. Because of the fact that the additional resistor 15 effects the increase in the negative bias applied to the control grid 21, the bias grid 21 controls the amount of plate current in the usual manner. More specifically, current from the battery 13 flowing through the resistance 15 will produce a voltage drop across that resistance which will be added to the voltage drop produced normally across the self-biasing resistor 14 and the combined voltage drops will be applied to the control grid 21 and increase the bias thereon in proportion to the value of the added resistance 15, and current through them.

To assume a specific example for the sake of illustration, the B battery 13 may supply 90 volts and the required D. C. voltage for the grid 21 is 4½ volts and the total B battery current required by all of the tubes in the set is 12 milliamperes. Under this set of conditions the value of the resistance 15 would be 375 ohms as determined in the usual way from the application of Ohm's law,

$$R = \frac{E}{I}$$

It is thus seen that the value of the additional biasing resistor 15 is determined by the amount of B current reduction desired which places a greater than normal negative biasing voltage on the control grid 21 of the output tube 10. Such an increase in bias voltage reduces the plate current of the output tube. Also the plate and screen currents of all of the other tubes in the circuit are reduced by the difference in voltage drop across the resistance 15 and the voltage drop across the combined resistors 14 and 15 in series. This combined voltage drop is subtracted from the total B voltage of the battery 13.

The two resistors 14 and 15 have been shown in Figure 1 as two separate resistors, but it is to be understood that a single resistance with conventional tap might be used. Also the resistors 14 and 15 may be made variable if desired.

As above indicated the switch 16 will permit the user of the radio set to have full volume from the receiver with the usual B battery current consumption; or reduced volume and reduced battery current with resulting longer B battery life. The switch 16 may be located on the front panel of the radio set and may be in the form of a simple toggle type of switch with an on-and-off position. One of the positions may be labeled, if desired, "economy position" which indicates that the resistance 15 is in circuit and the B battery current reduced.

As indicated in Figure 1 an alternative or combined means of extending the life of the B battery 13 comprises the use of taps 23 and a switch connector 24. By connecting the member 24 to different ones of the taps 23, the B battery voltage applied to the screen grid 20 may be varied. That is, the voltage on the screen grid 20 may be decreased to effect a decrease in the amount of plate current drawn by the plate 19. The switch means 24 may be connected independently or may be connected in tandem with the switching means 16 so that the effects may be applied singly or in combination.

Referring now to Figure 2, the curve 25 illustrates the B battery current, in milliamperes, consumed by the entire receiver when the output circuit of the receiver is operated in the conventional manner, that is, with normal bias on the grid of the output tube. An example of such operation would be that taking place in the cir-

cuit of Figure 1 when the resistor 15 was not in use. This curve shows that the B battery current used varies between about 10 to 25 milliamperes during the normal useful life of the B battery, that is, where it has a voltage supply of about 130 volts down to about 70 volts, when it is discarded.

Curve 26 illustrates the B battery current consumed when the circuit is operated in accordance with my invention, that is, when the over-bias resistor 15 is utilized. As shown by this curve the B battery current varies between about 7 to 15 milliamperes which constitutes a substantial reduction over the above normal operation.

The curves 27 and 28 complement the curves 25 and 26 and illustrate the difference in effective life of the B battery when operated under normal bias (curve 27) and when operated with over bias (curve 28), the latter being in accordance with my invention. As shown by these two curves the normal life of the B battery is increased from about 800 hours to about 1200 hours when using the over-bias feature of my invention.

I claim:

1. In a battery operated radio receiver having a plurality of tubes having screen grids, a common source of B voltage for a plurality of said tubes including the output tube, biasing means for controlling the potential of the control grid of the output tube, such biasing means utilizing a portion of said B voltage determined by a resistance in the common negative B return to the tube filaments, means for applying a positive potential to the screen grids of said plurality of tubes from said source of B voltage and means for manually reducing such resistance by a predetermined value whereby the control grid potential of the output tube may be reduced and

the B current thereby may be immediately greatly increased in the output tube and at the same time will also be increased in the remainder of said plurality of tubes.

5. 2. A radio receiver as defined in claim 1, in which the means for reducing such resistance comprises a manually operable switch for bypassing a portion of such resistance.

10 3. A radio receiver as defined in claim 1 which further includes a variable connector on the B battery for varying the amount of voltage supplied by said battery to a grid of said output tube.

15 4. In a battery operated radio receiver having a plurality of tubes having screen grids, a common source of B voltage for a plurality of said tubes including the output tube, biasing means for controlling the potential of the control grid of the output tube, such biasing means utilizing a portion of said B voltage determined by a resistance in the common negative B return to the tube filaments, means for applying a positive potential to the screen grids of said plurality of tubes from said source of B voltage, means for 20 manually reducing such resistance by a predetermined value comprising a switch for bypassing a portion of said resistance whereby the control grid potential of the output tube may be reduced and the B current thereby may be immediately greatly increased in the output tube, a variable connector on the B battery for varying the amount of voltage applied by said battery to a grid of said output tube and common means for varying said connector and operating said 25 switch whereby said resistance may be decreased and the amount of B voltage increased simultaneously.
